UNITED STATES PATENT OFFICE.

FANNIE H. SCHWARTZ, OF BROOKLYN, NEW YORK.

CONVERTIBLE GARMENT.

1,406,764.

Specification of Letters Patent. Patented Feb. 14, 1922.

Application filed January 25, 1918. Serial No. 213,752.

To all whom it may concern:

Be it known that I, FANNIE H. SCHWARTZ, a citizen of the United States, residing at Brooklyn, in the county of Kings and State 5 of New York, have invented new and useful Improvements in Convertible Garments, of which the following is a specification.

This invention relates to convertible garments.

10 The invention is particularly designed for use as a woman's under garment but the same is possessed of such functional features that will permit the same to be advantageously employed as an outer garment and to 15 have the effect of a riding habit, bloomers or the like.

An object of the invention resides in the provision of means which will permit the user to readily convert the garment from 20 one design to another, giving to the garment at all times, a tasteful and attractive formation.

25 With the above and other objects in view which will appear as the nature of the invention is better understood, the same consists in the improved construction and novel arrangements of parts which will herein-after be fully described and particularly pointed out in the claim.

30 In the accompanying drawings, has been illustrated, a single and preferred form of the invention, it being, however, understood that no limitations are necessarily made to the precise structural details therein exhibited, but that changes, alterations and 35 modifications within the scope of the claim may be resorted to when desired.

Figure 1 is a front view of the garment.

Figure 2 is a similar view, showing a different adjustment thereof.

Figure 3 is a section on line 3—3 of Figure 1.

Figure 4 is a section on line 4—4 of Figure 2.

45 The garment consists of an upper waist portion 10, and a lower skirt portion 11, it being preferred that the upper and lower portions be constructed from the same integral piece of material. The skirt portion 50 is divided or bifurcated at its center both at the front and at the back of the garment. At the back of the skirt portion of the garment, the portion 12 at one side of the center of the garment is provided along its edge 55 with a number of resilient heads or similar fastenings 13. At the other side of the

center of the garment, the portion 14, of the skirt section is provided with resilient sockets 15 which are adapted to mate with the heads 13 when the garment is adjusted as 60 shown in Figures 1 and 3. At the front the garment is formed in a similar manner, the portion 16 thereof at one side of the center having a number of resilient sockets 17 adapted to mate with resilient heads 18 on 65 the portion 19 of the garment at the front and at the other side of the center thereof. This arrangement permits of a skirt formation and the same can be conveniently employed either as an outer garment or an inner garment as will be fully understood.

The formation of the garment as above outlined, permits the user to readily convert the same from an apparently undivided skirt to a bifurcated or divided skirt as 75 shown advantageously in Figures 2 and 4. When it is desired to transform the garment from one design to another, the snap fastenings above mentioned, are manipulated and assuming it desirable to establish 80 the form of garment shown in Figures 2 and 4, said respective fastenings are all released from the positions which they occupied in Figures 1 and 3, and the fastenings 13, engaged with the fastenings 17, and the fastenings 15 engaged with the fastenings 18. This produces a bifurcated or leg effect at the skirt portion of the garment as clearly 85 shown in Figure 2. In order that each of said leg portions thus formed can be confined snugly against the leg of the user, use is made of elastic tapes 20—20, one being provided with each half of the skirt section of the garment. These tapes are secured to the lower ends of the leg portions, each tape 90 being provided with elements constituting the complementary members 25 and 26 of snap fastenings of well known construction. The tapes are permanently secured at one end only—the lower end in Figure 1—and 95 the free ends are attached to fastening members 21 on the outside of the garment when the latter is in skirt formation.

While it is described that the garment is only bifurcated through a certain portion of 105 its length, it nevertheless follows that it may be bifurcated substantially throughout its entire length and connected together in any suitable well known manner. In the present instance, it is preferred to seam the garment 110 at the front on a vertical line from the neck to the top of the bifurcated portion. When

used as an inner garment, various tasteful effects may be brought into vogue. The garment is simple of construction, attractive, extremely useful and is capable of being converted from a garment of one design to that of another at the option of the user.

What is claimed as new is:—

A one piece undergarment for covering the shoulders, body, and limbs, and comprising a waist section and a skirt section, the waist section having a closed front and back and the skirt section being divided vertically at the center of the front and back for forming two leg portions continuous with the waist, fastening devices on the inner edges of the leg portions, such devices being positioned to permit of engagement for fastening the garment around the limbs individually and for fastening the garment at other

times so that the front portion will be continuous transversely for forming the front of the skirt and the back portion will be similarly connected to form the back of the skirt, elastic tapes each having permanent connection at one end with the garment and adapted to encircle the leg of the wearer, a fastening device on the free end of each tape, a complementary fastening device on the other end of the tape, and a fastening device corresponding with that last named on the side of the garment and spaced from the permanently connected end of the tape, permitting the latter to be retained in an extended position along the side of the garment when said garment is in skirt form. 35

In testimony whereof I affix my signature.

FANNIE H. SCHWARTZ.
